UNITED STATES PATENT OFFICE.

EMIL BERTHOLD WALTER REICHEL, OF BERLIN, GERMANY, ASSIGNOR TO
THE SIEMENS & HALSKE ELECTRIC COMPANY OF AMERICA, OF CHICAGO,
ILLINOIS.

ELECTRIC-RAILWAY SYSTEM.

SPECIFICATION forming part of Letters Patent No. 617,837, dated January 17, 1899.

Application filed October 3, 1898. Serial No. 692,539. (No model.)

To all whom it may concern:

Be it known that I, EMIL BERTHOLD WALTER REICHEL, a subject of the Emperor of Germany, residing at Berlin, Germany, have
5 invented a certain new and useful Improvement
in Electric-Railway Systems, (Case No.
168,) of which the following is a full, clear,
concise, and exact description.

My invention relates to electric-railway systems, and particularly to those systems in which each train contains a plurality of motor-cars, each motor-car being attended by a motorman.

My invention has for its object the provision
15 of improved means for guiding the assistant
motormen in the operation of their controllers,
so that they may be informed of the condition
of use of the controller in charge of the chief
motorman upon the first car of the train. The
20 assistant motormen are thus enabled to place
their controller-handles in positions similar
to that occupied by the controller-handle man-
ipulated by the chief motorman.

The invention in its preferred embodiment
25 comprises a signal-circuit including a signal
upon each motor-car contained in the train
in addition to the leading motor-car, a switch-
arm mechanically connected with the controller
handle or lever operated by the chief mo-
30 torman being employed for governing the sig-
nal-circuit.

I will explain my invention more particu-
larly by reference to the accompanying draw-
ings, which illustrate one embodiment thereof.

35 Figure 1 of the drawings is a diagrammatic
view showing three motor-cars assembled
into a single train, the apparatus of my in-
vention being diagrammatically illustrated.

Fig. 2 is a plan view of a set of signals pro-
40 vided for the use of each of the assistant mo-
tormen.

Like letters and numerals refer to like parts
in both views.

In the drawings I have illustrated a motor-
45 train comprising a leading motor-car *a* and
two additional motor-cars *b b'*, each motor-
car being provided with a motor and supplied
with current from a generator *c* in a well-
known manner. Upon cars *a b b'* are pro-
50 vided suitable controllers, as the controlling-

rheostats *d d' d''*. In this particular instance
I have illustrated a supplemental contact-arm
e mechanically connected with the controller-
arm of rheostat *d*, whereby the arm *e* is actu-
ated upon the actuation of said controller-
arm. The arm *e* is preferably insulated from
the contact-lever of the controller and en-
gages a segmental plate *f* and successively
contact-buttons *f' f'' f'''*. The contact-buttons
and the contact-plate *f* form terminals upon
the car *a* of conductors 1, 2, 3, and 4, respec-
tively. These conductors extend to the cars
b b'. Signals *g g'* upon cars *b b'* are con-
nected between conductors 1 and 4, signals *h h'*
are connected between conductors 2 and 4, 65
and signals *i i'* are connected between conduct-
tors 3 and 4. The signals are placed within
sight of the assistant motormen. Circuit is
closed successively through the signals as the
switch-arm *e* is moved, the signals being suit-
70 ably designated to indicate to the assistant
motormen the position of the controller-lever
upon car *a*. The signals upon each car are
preferably grouped as shown in Fig. 2, which
illustrates in plan view a circular face hav-
75 ing three openings, preferably covered by
ground glass, behind which the signals, which
are preferably incandescent lamps, are dis-
posed. These lamps are successively lighted
as the controller-lever upon the leading car 80
is rotated. The assistant motorman changes
the position of his controller-lever upon the
extinguishment of a lamp to the position in-
dicated by the lamp next caused to glow.
Each group of signals constitutes an indicator
85 for showing the position of the controller-
lever operated by the chief motorman.

If it is desired, supplemental audible sig-
nals *k k'* may be provided upon the cars *b b'*.
The number of signals upon the motor-cars 90
may be varied, as desired. The conductors
1, 2, 3, and 4 are in sections, which are united
between the cars by flexible links 1¹ 2¹ 3¹
4¹ when the motor-cars are assembled into a
train. 95

The group of lamps located near each con-
troller to be within the presence of the mo-
torman operating the controller constitutes a
graduated indicator, serving to inform the
motorman of the position to which he should
100

move his controller, the switch operated by the chief motorman constituting a graduated means for operating the graduated indicator. Signals may be provided near that controller 5 which serves to govern the signals upon the remaining cars; but they are not absolutely essential, as the signals or indicators are provided for the information of the motormen upon the rear motor-cars. It may be desirable, however, to provide the signals upon the first motor-car in order that the motorman upon that car may know that the signaling-circuits are in proper working condition. I do not wish to be limited to the precise 15 position of the signals herein set forth.

It is obvious that other controlling devices than those herein diagrammatically illustrated may be employed in governing the motor-circuits. Other arrangements of signal-circuits and signaling apparatus may also be employed without departing from the spirit of the invention. I do not therefore desire to be limited to the precise system and apparatus shown; but,

25 Having described my invention, what I claim as new, and desire to secure by Letters Patent, is—

1. In an electric-railway system, the combination with a plurality of motor-cars in a single train, of motor-controllers upon said cars, an indicator upon one of the motor-cars, and means governed by the motor-controller upon another car for operating said indicator, substantially as described.

35 2. In an electric-railway system, the combination with a plurality of motor-cars in a single train, of motor-controllers upon said cars, a signal-circuit between the cars, an indicator upon one of the motor-cars in said circuit, and switching apparatus operated by the motor-controller upon another car for governing the said signaling-circuit, substantially as described.

3. In an electric-railway system, the combination with a plurality of motor-cars in a single train, of motor-controllers upon said

cars, a plurality of signals upon one of the cars, and means for operating said signals governed by the motor-controller upon another car, substantially as described.

50

4. In an electric-railway system, the combination with a plurality of motor-cars in a single train, of motor-controllers upon said cars, a plurality of visual signals upon one of the cars, and means for operating said signals governed by the motor-controller upon another car, substantially as described.

5. In an electric-railway system, the combination with a plurality of motor-cars in a single train, of motor-controllers upon said cars, a plurality of signal-circuits between the cars, a signal in each of said circuits located upon one of the cars, and a switch for successively opening and closing said circuits operated by the lever of the motor-controller upon another car, substantially as described.

6. In an electric-railway system, the combination with a plurality of motor-cars in a single train, of motor-controllers, one upon each of said motor-cars; an indicator located near one motor-controller to be within the presence of the motorman operating the latter controller, and means governed by another of said motor-controllers for operating said indicator, substantially as described.

70

7. In an electric-railway system, the combination with a plurality of motor-cars in a single train, of motor-controllers, one upon each of said cars; a graduated indicator located near one motor-controller to be within the presence of the motorman operating the latter controller, and graduated means for operating said graduated indicator, said means being governed by another of said motor-controllers, substantially as described.

75

In witness whereof I hereunto subscribe my name this 13th day of September, A. D. 1898.

EMIL BERTHOLD WALTER REICHE.
